UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

RADIANT HEATER.

Application filed May 19, 1923. Serial No. 640,047.

To all whom it may concern:

Be it known that I, ORA A. COLBY, a citizen of the United States, and a resident of Irwin, in the county of Westmoreland and State of Pennsylvania, have invented a new and useful Improvement in Radiant Heaters, of which the following is a specification.

My invention relates to electrically heated devices, and particularly to radiant electric air heaters.

One object of my invention is to provide a relatively simple and compact electric air heater comprising a plurality of radiant heating elements.

Another object of my invention is to provide an electric air heater of relatively large capacity comprising a plurality of radiant heating elements distributed substantially uniformly over the front of a reflector plate.

Another object of my invention is to provide an electric air heater comprising a plurality of radiant heating elements of twisted flattened helices of resistor wire suspended in festoons in front of a reflector plate.

In practicing my invention, I provide a casing in which is located a reflector plate of refractory electric-insulating material having a plurality of spaced rows of integral, spaced, and relatively small lugs on its front surface. A plurality of heating elements, each comprising a twisted flattened helix of a resistor conductor are supported in the form of festoons from and between adjacent pairs of lugs.

In the single sheet of drawings,

Figure 1 is a view, in front elevation, of an electric air heater embodying my invention.

Fig. 2 is a view, in vertical section, taken on the line II—II of Fig. 1, and

Fig. 3 is an enlarged view, in front elevation, of a part of a heating element embodying my invention.

An electric air heater 11 comprises a casing 12 that may be built up in any suitable or desired manner either by the use of sheet metal members or by the use of suitable castings to constitute a casing of pleasing and ornamental appearance.

The casing 12 is mounted on a suitable base 13 having integral supporting members 14. A top or cover member 15 is provided that may be made removable to permit of mounting the other parts of the electric

heater within the casing. The front of the casing is provided with a depressed portion 16 having a front opening 17 therein. An ornamental and protective grating 18 comprises a plurality of rods or wires extending substantially at right angles to each other, the upper ends of the vertically extending rods fitting loosely into spaced openings 19 in the upper part of the depressed portion 16 and the lower ends of the vertically extending rods fitting into openings 21 in the lower part of the depressed portion 16. A rod 22 is secured to the lower end of the vertically extending rods and it holds the grating 18 in substantially the position illustrated in Fig. 2 of the drawing after the same has been placed in its proper operative position by a tilting and lateral movement thereof.

A reflector plate 23 of a suitable electric-insulating material, which is mounted in the casing 12 in back of the opening 17, may be supported in any suitable or desired manner within the casing, as by being mounted on a plate 24 extending across the casing 12 below the opening 17. The plate 23 is provided with a plurality of spaced rows of integral, spaced lugs 25 that are severally provided with an opening 26 extending therethrough, and also extending through the plate 23.

A plurality of individual heating elements 27 are suspended in the form of festoons between two adjacent and horizontally-spaced lugs 25 by their ends which extend through the openings 26 to the back of the reflector plate. Each of the elements 27 comprises a twisted flattened helix, of a suitable resistor, substantially as illustrated in Fig. 3 of the drawing, in which only a part of an individual heating element is illustrated.

Any desired number of heating elements 27 may be provided in front of the reflector plate 23, the number of integral lugs 25 extending in a substantially horizontal row across the front of the plate, being one greater than the number of individual heating elements 27 supported thereby.

Any desired number of lugs and of festoons of heating elements may be provided and I have shown four festoons in horizontal row, connected in series circuit relation relatively to each other and four sets of said rows.

Bus bars 28 and 29 may be provided within the casing adjacent each side thereof, to which the sets of heating elements 27 are connected in series circuit relation relatively to each other may be connected. It is understood, of course, that the adjacent ends of the heating elements 27 intermediate the outer elements are electrically connected to each other by any suitable or desired means.

10 A controlling switch 31 is mounted on a plate 32 of a suitable electric-insulating material that is secured against the side of the casing by screws 33. Contact terminal pins 34 are also mounted on the face plate 32 and the bus bars. The terminal pins and controlling switch are so connected that the switch 31 may be employed to control the energization of the heating elements.

While I have illustrated particular embodiments of the control device, I do not desire to be limited thereto, as an electric air heater of the type disclosed and described in this application may have associated therewith a control system of the kind described and claimed in a co-pending application of Victor G. Vaughan, Serial No. 641,054, filed May 24, 1923, and assigned to the Westinghouse Electric & Manufacturing Company (case 10399).

35 The device embodying my invention provides an electric air heater that has relatively few parts and that may be built to comprise sufficient heating elements to have a relatively large heat-translating capacity. 35 The form of the individual heating elements is such as to present a pleasing appearance when they are traversed by a sufficient electric current to cause them to become substantially incandescent and their form when 40 suspended, viz. that of festoons, further accentuates the pleasing appearance thereof.

The heating elements are distributed substantially uniformly over the front of the reflector plate, thereby insuring uniform heating of the individual heating elements and a maximum efficiency of radiation of heat therefrom.

Various modifications and changes may be made without departing from the spirit and scope of the invention, and I desire, therefore, that only such limitations shall be placed thereon as are imposed by the prior art or are set forth in the appended claims.

I claim as my invention:

1. An electric heater comprising a reflector plate of refractory electric-insulating material, and a plurality of individual heating elements hung in festoons in front of said plate.

2. An electric heater comprising a reflector plate of refractory electric-insulating material having a plurality of spaced integral lugs projecting from one surface thereof, and a plurality of individual heating elements supported respectively from 65 pairs of lugs in front of said plate.

3. In an electric heater, in combination, a reflector plate of refractory electric-insulating material, and a heating element comprising a twisted, flattened, helix of resistor 70 wire.

4. An electric air heater comprising a reflector plate of refractory electric-insulating material having a plurality of spaced, integral lugs projecting from one surface 75 thereof, and a plurality of heating elements supported by adjacent pairs of said lugs and each comprising a twisted, flattened helix of a resistor conductor.

5. An electric air heater comprising a reflector plate of refractory electric-insulating material having a plurality of rows of spaced, integral lugs on one surface thereof, and a plurality of heating elements each comprising a twisted, flattened helix of a 85 resistor conductor, each having its ends located in said lugs and having a length greater than the distance between adjacent lugs.

In testimony whereof, I have hereunto 90 subscribed my name this 15th day of May, 1923.

ORA A. COLBY.
